CLAIM

The ornamental design for an apparatus for cooling air, as shown and described.

DESCRIPTION

FIG. 1 is a front perspective view of an apparatus for cooling air showing the new design;
FIG. 2 is a top view thereof;
FIG. 3 is a right side view;
FIG. 4 is a left side view;
FIG. 5 is a front view;
FIG. 6 is a rear view; and,
FIG. 7 is a bottom view.

The broken lines in the drawings illustrate portions of the apparatus for cooling air which forms no part of the claimed design.
